(57) **CLAIM**

The ornamental design for a tire, as shown and described.

DESCRIPTION

FIG. 1 is a top perspective view of a tire showing a new design;

FIG. 2 is an enlarged top perspective view of a portion thereof;

FIG. 3 is a front elevation view thereof;

FIG. 4 is a top plan view thereof; and,

FIG. 5 is an enlarged top plan view of a portion thereof. The broken line showing of a tire is for the purpose of illustrating portions of a tire that form no part of the claim.
